CLAIM

The ornamental design for a teether, as shown and described.

DESCRIPTION

FIG. 1 is a top rear left perspective view of a teether showing our new design;

FIG. 2 is a right side elevation view thereof;

FIG. 3 is a left side elevation view thereof;

FIG. 4 is a top plan view thereof;

FIG. 5 is a rear elevation view thereof;

FIG. 6 is a bottom plan view thereof; and,

FIG. 7 is a front elevation view thereof.

The broken lines shown in the drawings illustrate portions of the teether that form no part of the claimed design.
